[57] ABSTRACT

An elongated joining or splicing member for joining together two elongated rigid structures along adjacently disposed but spaced-apart ends thereof. The joining member has a web or tail portion and a channel portion at one end of the web portion for engaging and joining the ends of the rigid structures together when the web portion of the joining member is moved into locking engagement with one of the rigid structures.

FIG. 2.

FIG. 3.

JOINING MEMBER FOR BUILDING CONSTRUCTIONS

BACKGROUND OF THE INVENTION

The present invention relates generally to building constructions, and particularly to a splice or joining member capable of positively securing together two rigid, spaced-apart structures, i.e., structures that cannot be placed in the proximity of each other required to receive a joining member of the type, for example, shown in U.S. Pat. No. 3,232,395 issued to R. L. LaBarge on Feb. 1, 1966.

In joining together adjacent panels in building constructions, for example, joining together pre-formed panels that provide exterior wall structures for buildings, the panels are joined together by simply moving the end or end face of one panel close to the end of the other panel, and then disposing a channel member in place over return bend portions of the panel ends. With the channel member in place about the return bends, the panels are moved apart until the return bends engage the channel member. The channel member is then fixed in place by a snug seam filler or member forced into the channel between the ends of the adjacent panels.

However, not all adjacently located building panels and associated structures, that need to be joined together, can be moved into the necessary proximity of the adjacent structure to allow the channel member to clear the return bends. Often, both adjacent structures are firmly fixed in place, or there is an obstruction which prevents two structures from being placed in close proximity for the channel member.

For example, in U.S. Pat. application Ser. No. 46,634, filed June 16, 1970, J. D. Klingensmith and B. C. Merkin and entitled "High-Strength Wall Structure with Sill and Header Members," a highly rigid wall structure is disclosed in which a ribbed panel, i.e., a panel having raised and valley portions extending the height thereof, is provided with sill and header members firmly clamped on the bottom and top of the panel, the sill and header members, with associated clamping members, having tongues and notches seated in and around respectively the valley and raised portions of the panel. In constructing a building with such wall structures, cornerposts are used to connect the panels at the corners of the building. Both the posts and the panels are provided with integral, elongated return, end portions for joining purposes. The posts, however, cannot be moved against or in the proximity of the panel necessary to permit a channel member to clear the return bends because the sill and header members and their respectively clamping members extend a distance beyond the end of the panel. The post and panel are positioned as close to each other as the sill and headers will allow, the space between them being capable of accepting an elongated filler member, for example, as shown in the above-mentioned LaBarge patent.

BRIEF SUMMARY OF THE INVENTION

The present invention provides a simple device for joining together, in an expedient manner, two spaced-apart structures that cannot be moved together to provide clearance for the disposition of a channel member over return bend portions of the spaced-apart structures. Briefly, this is accomplished with an elongated joining member having a tail or web portion provided with a notch extending the length of the web, and a channel portion at one end of the web for engaging and joining the ends of the spaced structures. At least one leg of the channel has a bent or return bend configuration in cross section corresponding to the return bends of the structures. To join the structures together, the bent leg of the joining member is simply disposed to engage the return bend of one of the structures and then swung or rotated toward the second structure until the other leg of the channel portion engages the return bend of the second structure, and a projection extending from one of the structures snaps into the notch in the web of the joining member. The projection deflects when the notch of the web is moved thereagainst, the projection then springing back to seat in the notch. This locks the joining member in joining relation across the ends of the structures.

THE DRAWINGS

The invention, along with its advantages and objectives, will be best understood from consideration of the following detailed description in connection with the accompanying drawing in which:

FIGS. 1 to 3 are cross-sectional views of elongated rigid structures with the joining member of the present invention shown in three successive positions in the process of joining together two of the structures.

PREFERRED EMBODIMENT

The figures of the drawing show a cross-sectional view of an elongated post 1 (extending into the plane of the paper) positioned between two exterior wall structures 2 and 3 to join the structures together in a watertight manner at the corner. The post is a rigid structure and preferably an extruded metal member though the invention is not limited thereto. The wall structures 2 and 3 are preferably rigid, preassembled units in which ribbed panels 5 and 6 are provided with sill and header members clamped to the bottom and top thereof as shown and described in the above-mentioned Klingensmith and Merkin application though other wall structures may be used in the practice of the invention. In the views of the present figures, only the sills are visible, the sills being designated by numerals 7 and 8.

As explained in the Klingensmith and Merkin application, the sill and headers are provided with tongue and notches which engage the panels on one side thereof while clamping members 9, having similar tongues and notches, engage the panel on the other side thereof. In the views of the figures, the upper surfaces of the sills 7 and 8 are visible on both sides of the panels 5 and 6, and the sills abut directly against the sides of the post 1 (with the headers not shown) as indicated at 7A and 8A. This is done for aesthetic purposes. Otherwise, a gap between the post 1 and the walls 2 and 3 would be the result, i.e., the gap would be visible from outside of a building constructed with the posts and panels as thus far described. The clamping members 9, however, are cut short of the post, as indicated, since they lie behind the panels, to provide clearance for the insertion of the joining member of the invention presently to be described. Upper flange portions 7B and 8B of the sills 7 and 8 are also visible in the figures.

The end faces of the panels 5 and 6 and the end faces or sides of post 1, as shown in the figures, are provided with integral return bend portions 10 and 11, respectively, for joining purposes as explained hereinafter.

In assembling a wall structure to include the corner posts 1 for say shipping purposes, the post 1 and the wall 2 are joined together before the sill and header members are clamped to the panel 5 of the wall. To join the post 1 and panel 2, the two structures are simply moved together and the return bend 10 of the panel 5 is disposed in engagement with an integral, curved extension 12 of the post on the side of the extension facing the return bend 11. Thereafter, as suitable filler strip 13 is inserted between the return bends 10 and 11 to provide a watertight seal between the post and panel, and the sill and headers are then clamped to the panel. A complete wall structure would include a post (not shown) joined to the other side of the wall 2 in the manner just described. Such a preassembled wall construction provides an essentially flat package configuration so that it can be shipped to say a building site with relative ease. To join, however, a second wall, wall 3 for example, to the post 1 at a right angle to the first wall 2 would provide a construction wholly unsuitable for transportation. Thus, the second wall 3 is preassembled (with sill and header) without posts affixed to the ends thereof so that it too can be transported as a relatively flat package. At the building site, the wall 3 can then be joined to the posts 1 in the manner presently to be explained.

When the preassembled wall structure 3 is disposed in position to be joined to the post 1 in the erection of a building, the ends 8A of the sill and headers prevent the post 1 and the panel 6 from being disposed in a manner to allow an integral

clamp of the post to clear the return bend portion 10 of the panel, as described in connection with the wall 2 and the integral projection 12 of the post. Nor is it possible to clear the return bends of the post and panel with a separate channel clamp of the type, for example, shown in the LaBarge patent.

In accordance with the invention, the wall 3 is easily joined or spliced to the post 1 by an elongated joining member 15 in cooperation with an elongated projection 16 integral with and extending from the side of the post toward the panel 6. More particularly, the joining member comprises an open-ended channel portion 18 located at one end of a web or tail portion 19. The channel portion includes two legs 20 and 21, the leg 21, which is closest to the panel 6, having a bent configuration conforming to the return bend 10 of the panel. The web of the joining member has a notch 22, extending lengthwise of the web, dimensioned to receive the projection 16 of the post therein.

To join the wall 3 and the post 1 together, the joining member 15 is moved into the area between the panel and post, as indicated by the arrow line 23 in FIG. 1, with the channel end 18 of the member facing in the direction of the return bends 10 and 11 of the panel and post. The bent leg 21 of the channel is next seated in the curve of the return bend 10 along its length and on the side thereof opposite to the return bend 11, as shown in FIG. 2. With the leg 21 so seated, the web of the joining member is rotated toward the post, as indicated by the arrow line 25 in FIG. 2, about the hinge or pivot point provided by the curved portions of the return bend 10 and the leg 21. The joining member is rotated until the leg 20 of the joining member engages the return bend 11 of the post on the side facing the post, and web portion engages and deflects the projection 16 of the post to allow the notch 22 of the web to move over the projection, at which time the projection springs back to seat in the notch to thereby lock the joining member in securing engagement with the ends (10 and 11) of the panel and post, as shown in FIG. 3 of the drawing. No further maneuvering of the joining member is necessary, and no other components are required to join the ends of the structures 1 and 3 together.

To provide the splice provided by the joining member 15 as described with a watertight seal, an elongated snug seam, filler strip 28 (FIG. 3) is forced into the space between the return bends 10 and 11 and into the area of the channel 18 of joining member 15.

From the foregoing description it should now be apparent that a simple and highly expedient joining member and arrangement have been disclosed in which a single member is simply rotated into locking engagement with elongated, spaced-apart, rigid structures to be joined. This is accomplished by use of an elongated joining member having a web or tail portion with a notch therein, and a channel at one end of web for engaging the ends of the two rigid structures in joining relation. To join the structures, one leg of the channel is

disposed to seat in a return bend of one of the rigid structures, and the joining member swung toward the other structure until the other leg of the channel engages the return bend of the other structure and the notch of the web snaps into locking engagement with a projection extending from one of the structures.

While the invention has been described in terms of preferred embodiments, the claims appended hereto are intended to encompass all embodiments which fall within the spirit of the invention.

Having thus described my invention and certain embodiments thereof, I claim:

1. An elongated joining member for positively securing together two rigid structures along adjacently disposed but spaced apart end faces thereof in which each of said end faces has a return bend extending lengthwise of said structures and at least one of said structures has a projection extending lengthwise thereof,

20 said joining member having a web portion and a channel portion at one end of said web portion, said channel portion having at least one leg provided with a return bend for engaging the return bend of one of said structures,

25 the web portion of said joining member having a notch extending lengthwise thereof for engaging the projection provided on said one structure, to lock the joining member in place in joining engagement with the return bends of said rigid structures when the return bend of the channel portion of said joining member is disposed to engage the return bend of one of said structures, and rotated toward the second structure until the other leg of said channel engages the return bend of the second structure and the projection seats in the notch of said joining member.

30 35 2. In a building construction including at least two adjacent structures having adjacently disposed but spaced-apart return bend portions extending along the ends thereof, and at least one of said structures having a projection extending lengthwise thereof,

40 45 an elongated joining member positively securing said structures together, said member having a web and channel portions, the channel portion having at least one leg provided with a bend corresponding to the return bends of said spaced-apart structures engaging the return bend of one of said structures,

50 the web of said joining member having a notched portion extending the length thereof engaging the projection on said one structure to lock said joining member in place with the channel portion thereof in joining engagement with the return bends of said spaced apart structures.

55 3. The structure of claim 2 in which one of the spaced-apart structures is a corner post of a building construction, and the other structure is a wall panel of said building construction.

UNITED STATES PATENT OFFICE
CERTIFICATE OF CORRECTION

Patent No. 3,636,668 Dated Jan. 25, 1972

Inventor(s) James D. Klingensmith

It is certified that error appears in the above-identified patent and that said Letters Patent are hereby corrected as shown below:

Col. 1, line 27	Change "to" to --the--
Col. 1, line 30	After "1970" insert --by--
Col. 1, line 42	After "return" delete the comma and change "end" to --bend--
Col. 1, line 47	Change "pose" to --post--
Col. 2, line 20	Change "heater" to --header--
Col. 2, line 28	Change "tongue" to --tongues--
Col. 2, line 40	Change "indicted" to --indicated--

Signed and sealed this 22nd day of August 1972.
